UNITED STATES PATENT OFFICE

GEORGE S. ANDREWS, OF SAN FRANCISCO, CALIFORNIA.

IMPROVEMENT IN CASTERS.

Specification forming part of Letters Patent No. **222,226**, dated December 2, 1879; application filed May 22, 1879.

To all whom it may concern:

Be it known that I, GEORGE S. ANDREWS, of the city and county of San Francisco, and State of California, have invented a Brake-Attachment for Furniture-Casters; and I do hereby declare that the following is a full, clear, and exact description thereof, reference being had to the accompanying drawings.

The object of my invention is to arrange furniture-casters so that they will rotate freely under the ordinary weight of the piece of furniture to which they are attached, but be cramped, bound, or chocked so as to form a solid bearing when any additional weight is placed upon the article of furniture.

To do this I place a spring or cushion in the bottom of the socket in which the spindle of the caster is inserted, so that the end of the spindle will press upon it. I also arrange the spindle so that it can move longitudinally a limited distance through the cap which covers the end of the leg and socket. The ordinary weight of the article of furniture will then be supported by the spring, and the caster will operate freely, but if additional weight be applied the wheel will be blocked and prevented from rotating.

In order to illustrate my invention I have represented it in the accompanying drawings in connection with a piano-stool, to which article of furniture it is more particularly adapted, but it can also be applied to other articles of furniture.

Figure 1 is a vertical section of my improved caster. Fig. 2 is an elevation of the same, and Fig. 3 is a detached view of a piano-stool provided with my improved automatic caster-brake.

A is a piano-stool or other article of furniture. B is an ordinary furniture-caster having the usual spindle C, which projects up into a socket in the bottom of the stool-leg D. In applying the caster to the leg D, I make the socket somewhat deeper than usual, and in its bottom I place a block, e, of india-rubber or other elastic cushion or spring. I then drop a metallic plate, i, loosely into the socket, so that it will rest upon the cushion or spring.

Upon the spindle C of the caster I place a

disk or cap, f, which has a hole through its center, and a tubular extension, j, projecting from it on one side. This tubular extension is shorter than the spindle, so that when the spindle is passed through it and its end headed down so as to prevent it from slipping out it will have a longitudinal play through the disk and tubular extension. The disk is large enough to cover the end of the leg D. When the tubular extension has been slipped into the socket in the leg, I secure the disk to the bottom of the leg by means of screws in the ordinary way. The end of the spindle will then press upon the spring and the weight of the stool or other article to which the caster is applied will be supported by the spring when the caster rests upon the floor, but if an extra weight, such as the weight of a person, be placed upon the stool the spring or cushion will be condensed until the caster-wheel strikes against the under side of the disk or cap f, by which means the wheel is blocked and the caster prevented from rotating.

This provides a solid bearing for the stool when it is occupied, so that it will not move upon its rollers, but when the weight is removed the elasticity of the spring raises the stool until the caster-roller is free to rotate as usual. The end of the spindle bears against the metal plate i in the socket, so that the cushion or spring is not injured, and there is but little friction to prevent the free rotation of the spindle. An elastic or roughened surface could be applied to the under side of the cap or disk f, so as to increase the friction of the wheel against it, and thus render the brake more positive.

Various applications of a spring or cushion could be made to accomplish the same purpose, but these would be simple equivalents for the device shown.

I am aware that spring-casters have been used for accommodating inequalities of the floor on which the article of furniture stands, or inequalities in the length of the legs, but the application of a brake to the wheel by the compression of a spring or cushion is the feature that makes my arrangement valuable.

Having thus described my invention, what

I claim, and desire to secure by Letters Patent, is—

1. The combination, with a caster-wheel frame and a spring, of a standard adapted, by the exertion of downward pressure thereon, to compress the spring and brake the wheel, substantially as specified.

2. The cap or disk *f*, with its tubular extension, *j*, in combination with the spindle *C*, of a furniture-caster, said spindle having free rotation and longitudinal play in the tubular

extension, and the elastic cushion or spring *e*, with its interposed metal plate *f*, all combined and arranged to operate substantially as and for the purpose described.

In witness whereof I have hereunto set my hand and seal.

G. S. ANDREWS. [I. S.]
